DESIGN FOR A PORTABLE ELECTRIC LIGHTING FIXTURE

David J. Biller, St. Louis, Mo., assignor to Day-Brite Lighting, Inc., St. Louis, Mo., a corporation of Missouri

Application January 2, 1943, Serial No. 109,193

Term of patent 7 years

To all whom it may concern:

Be it known that I, David J. Biller, a citizen of the United States and a resident of the city of St. Louis and State of Missouri, have invented a new, original, and ornamental Design for Portable Electric Lighting Fixture, of which the following is a specification, reference being had to the accompanying drawing, forming part thereof.

Fig. 1 is a side elevational view of a portable electric lighting fixture, showing my new design, the hinged and pivoted bail forming part of said fixture being shown turned under one end to support the same in reclining position,

Fig. 2 is an end elevational view of the bail end of the fixture,

Fig. 3 is an end elevational view of the opposite end of the fixture,

Fig. 4 is a cross-sectional view of the fixture on the line 4—4 in Fig. 1; and

Fig. 5 is a side elevational view of the fixture looking at the reflector side thereof, the fixture being shown in upright position with the bail in position for suspending the fixture in such position.

I claim:

The ornamental design for a portable electric lighting fixture, as shown and described.

DAVID J. BILLER.
